UNITED STATES PATENT OFFICE.

PHILLIP KNORPP AND GUSTAV A. MAYER, OF STAPLETON, NEW YORK.

MACHINE FOR MAKING CONFECTIONERY.

SPECIFICATION forming part of Letters Patent No. 407,935, dated July 30, 1889.

Application filed April 19, 1889, Serial No. 307,720. (No model.)

To all whom it may concern:

Be it known that we, PHILLIP KNORPP and GUSTAV ADOLPH MAYER, both of Stapleton, in the county of Richmond and State of New York, citizens of the United States, have invented certain new and useful Improvements in Machines for Making Confectionery, of which the following is a specification.

The object of this invention is to furnish
10 an improved machine for making an article
of confectionery in which letters or other designs
are produced in paste on a foundation
of paper or other suitable material, which
confectionery forms the subject-matter of a
15 concurrent application for Letters Patent filed
April 17, 1889, and serially numbered 307,543;
and the invention consists of a machine for
making confectionery comprising a receptacle
for sugar paste or other similar mass, a follower
20 in said receptacle, a perforated bottom plate
in said receptacle for the design to be produced,
a vertically-reciprocating table below
said receptacle, said table being provided
with transverse spring-actuating keepers for
25 holding the paper or other foundation for the
paste designs in position on the table, and
fixed stops below said keepers for releasing
the same from the table to permit of the
forward feeding of the paper for the length
30 required.

In the accompanying drawings, Figure 1
represents a vertical transverse section of
our improved machine for making confectionery
on the line x x , Fig. 2, some of the
35 parts being broken away. Fig. 2 is a front
elevation of the same with a part of the
receptacle for the paste broken away, and
Fig. 3 represents a face view of the article of
confectionery to be made by the machine.

40 Similar letters of reference indicate corresponding parts.

Referring to the drawings, A represents
the supporting-frame of our improved
machine for making confectionery. At the up-
45 per rear part the frame is provided with vertical
standards A, which are extended in up-
ward direction so as to support a receptacle
B for the sugar paste required for making
the confectionery. The receptacle B is at-
50 tached to the standards A' by means of lugs
b, which are attached thereto by clamp-
screws b', as shown in Fig. 2. The bottom B'

of the receptacle B is perforated according
to the design to be produced, and the paste
is forced out through the perforated bottom 55
by means of the follower C, which is forced
down on the body of paste in the receptacle
B by a lever D, which is provided with a piv-
oted and spring-actuated pawl d, that engages
the rack-shaped stem C' of the follower C. 60
The lever D is fulcrumed to a transverse
piece connecting the upper parts of the standards A' and guided at its front end in a fork
D', which is hinged to the front part of the
receptacle B and retained thereon by a key 65
d', which is passed through keepers d², as
shown in Figs. 1 and 2. The rear end of the
lever D is acted upon by a spiral spring D³,
which is attached thereto and to the frame
A, so as to exert a lifting action on the lever 70
as soon as the same is released.

The follower rod or stem C' is guided be-
tween the lever D and the guide-disk d³, the
shank of which passes through a slot d⁴ of the
lever D, and is retained by a thumb-nut d⁵, 75
as shown in Fig. 2. Whenever it is desired
to insert a new supply of paste into the re-
ceptacle B, the front guide-fork D' is released
and moved into the lowered position and the
guide-disk d³ is loosened and moved to the 80
lower end of the slot d⁴, so as to clear the fol-
lower-stem C'. The follower C is then raised,
removed laterally, and the receptacle B re-
filled with a new supply of sugar paste and
the guide-disk d³ brought back into the posi- 85
tion shown in Fig. 1 and locked in place.

Below the receptacle B is arranged a table
E, that is supported on a vertical rod E', which
is guided in sleeves of the cross-pieces A² of
the frame A. The lower end of the vertical 90
table-supporting rod E is connected with ful-
crumed and weighted lever E', which imparts
a lifting action on the table E, so as to move
the same up in contact with the bottom of the
receptacle B, said lever being mounted on a 95
cross-rod E² of its frame. For moving the
table E in downward direction away from the
receptacle the hand-wheel f on the shaft F
is turned so that a pinion f', which meshes
with a rack at the rear side of the vertically- 100
supporting rod E, moves the table in down-
ward direction against the tension of the
weight D'. On the shaft F is arranged a
ratchet-wheel f², which is engaged by a piv-

oted and spring-actuated pawl f^3 , which is extended toward the front part of the machine in the form of a lever f^4 , which lever, when depressed, disengages the pawl f^3 from the teeth 5 of the ratchet-wheel f^2 . For lowering the table E the pawl f^3 has to be disengaged and simultaneously the hand-wheel f turned. When the table is lowered as far as required, the pawl f^3 is permitted to engage the ratchet-wheel f^2 , so as to lock the table in position 10 until it is released by pressing the pawl-lever f^4 in downward direction.

The table E is provided at both ends beyond the outer sides of the receptacle B with 15 transverse keepers g , which are applied to the upper ends of the guide-rods g' , which pass through holes of the table, and are connected at their lower ends by bars g^2 .

Spiral springs g^3 are interposed between 20 the under side of the table E and the lower bar g^2 , said springs serving to retain the keepers in contact with the top surface of the table E as soon as the lower bars g^2 are raised above the fixed stops h , which are held in the 25 upper cross-pieces A^2 by means of suitable set-screws h' . As soon as the table E is raised and the bars g^2 moved away from the stops h the spiral springs g^3 cause the downward motion of the keepers g , and they serve thereby 30 to hold a continuous strip M of paper that is passed over the top surface of the table E rigidly in position on the said top surface of the table. As soon as the table is lowered and the bars g^2 are brought in contact with 35 the stops h , the keepers are raised above the table, and thereby the paper released, so that the same can be pulled forward and a new piece of paper placed below the receptacle B. The paper is supplied from a roll G, the shaft 40 of which is supported in bearings at one end of the table E, as shown in Fig. 2. The paper strip or band is properly perforated according to the length of foundation required for each article of confectionery made thereon, so that they can be readily separated into 45 proper lengths after the designs have been transferred to the same and dried in suitable drying-rooms. From the table E the strip passes upon an endless conveying-belt 50 H, (shown in Fig. 2,) from which it is conveyed to the drying-rooms for drying the paste deposited thereon from the receptacle.

Our improved machine for making articles of confectionery is operated as follows: A 55 strip of paper of proper length is placed below the perforated bottom of the receptacle B, and clamped on the same by raising the table by the influence of the weighted lever at its lower end on releasing the pawl-lever f^3 60 from the ratchet-wheel f^2 . By the raising of the lever the keepers g are applied tightly to the paper strip supported on the top surface of the table. When the table is thus raised against the bottom of the receptacle B, the lever D is taken hold of and the follower pressed downward, so that a quantity of paste 65

sufficient for forming the design on the paper is ejected through the openings of the perforated bottom. The table is then lowered and the keepers removed from the paper by 70 the contact of their lower bars g^2 with the stops h . The paper is then moved forward from the table toward the right upon the conveying-belt H and a new length of paper placed below the receptacle. The table is 75 then raised again and placed below the bottom of the receptacle, the next design is ejected from the receptacle, as before described, and so on. In this manner the articles of confectionery of the character described can be made quickly and at a very low price.

Our machine is also adapted for making other articles of confectionery in which a suitable ornamentation of icing or a paste is used, 85 in which case the articles of confectionery have to be placed on the table in suitable trays and supplied with icing by the lowering of the follower in the manner before described.

Having thus described our invention, we claim as new and desire to secure by Letters Patent—

1. In a machine for making confectionery, the combination of a paste-receptacle having 95 a perforated bottom and a follower guided in said receptacle, a vertically-guided table below the receptacle, transverse and spring-actuated keepers at the ends of the table, and fixed stops below said keepers, so as to raise 100 the same against the tension of the springs when the table is lowered, substantially as set forth.

2. In a machine for making confectionery, the combination, with a paste-receptacle having 105 a perforated bottom, of a follower the follower-rod of which is provided with a rack-bar, a fulcrum and spring-actuated lever, a hinged fork for guiding the front end of the lever, a pivoted and spring-actuated pawl 110 on said lever for engaging the rack of the follower-rod, and means for guiding the follower-rod along the lever, substantially as set forth.

3. In a machine for making confectionery, the combination, with a vertically-guided 115 table having a vertically-adjusting rack-bar, a fulcrum and weighted lever connected with the lower end of said rack-bar, a pinion engaging said rack-bar, a hand-wheel on the shaft of the pinion for turning the shaft and 120 lowering the table, and a pawl-and-ratchet-device for locking the pinion and rack-bar in position, substantially as set forth.

In testimony that we claim the foregoing as our invention we have signed our names in 125 presence of two subscribing witnesses.

PHILLIP KNORPP.
GUSTAV A. MAYER.
